INVENTOR.

William C. Bowlen,

BY

Frank A. Cutler,

ATTORNEY.

UNITED STATES PATENT OFFICE.

WILLIAM C. BOWLEN, OF HOLYOKE, MASSACHUSETTS.

PLANE.

1,342,154.

Specification of Letters Patent. Patented June 1, 1920.

Application filed January 13, 1920. Serial No. 351,145.

To all whom it may concern:

Be it known that I, WILLIAM C. BOWLEN, a citizen of the United States of America, and a resident of Holyoke, in the county of 5 Hampden and State of Massachusetts, have invented new and useful Improvements in Planes, of which the following is a specification.

My invention relates to improvements in 10 planes and more especially to the adjusting means for the plane-irons, and consists essentially of a horizontally adjustable member to the forward end of which the plane-iron is secured, and an oblique locking member for said first-named member, together with such other parts and members as may be necessary or desirable in order to render the plane which is equipped with the new 15 adjusting means practicable, serviceable, and efficient in every respect, the construction and arrangement of parts and members being such that said horizontally adjustable member and said locking member are readily accessible, all as hereinafter set forth.

The primary object of my invention is to 20 provide a plane with adjusting means for the plane-iron, which means not only are simple in construction and operation, strong and durable and highly efficient, but are 25 readily accessible, so that the plane does not have to be taken down or any part thereof be removed, when it is desired to adjust said plane-iron forward or backward, and can be 30 most conveniently operated to obtain the results desired, the application of a screwdriver at two freely conspicuous points being all that is required in order to make 35 whatever adjustment is desired at any time.

Another object is to construct the plane 40 in such a manner that the supporting member for the plane-iron is at all times held and guided in a fixed path which lies in the central, longitudinal, vertical plane of the implement.

Other objects and advantages will appear 45 in the course of the following description.

I attain the objects and secure the advantages of my invention by the means illustrated in the accompanying drawings, in

50 which—

Figure 1 is a longitudinal, central, vertical section through a plane which embodies a practical form of my invention; Fig. 2, a 55 rear end elevation of certain of the new elements, the view being taken on lines 2—2,

looking in the direction of the associated arrow, in Fig. 1, and therefore being a cross section through the frame of the plane; Fig. 3, a fragmentary detail in top plan of the parts and members shown in the preceding 60 view, and, Fig. 4, a detail in side elevation of the link.

Similar reference numerals designate similar parts throughout the several views.

Although I have illustrated a complete 65 plane, it will not be necessary to describe all of the parts thereof and their functions, but only those into combination or close association with which the new adjusting means enter and to which they directly relate. I will first, therefore, point out or describe briefly the old elements in question.

The frame of the plane consists of a sole 1 and cheek pieces 3—3 as usual, and is provided with ordinary front and rear handles 4 and 5, respectively. A plane-iron or blade 6 is represented at 6, and a stiffener therefor at 7, the two being fastened together by a screw 8. The sole 1 has therein a throat 9 for the cutting edge of the blade 6. There 80 are also a clamp 10 which has a slot 11 therein, a lever 12 to adjust the blade 6 longitudinally, with a thumb-screw 13 therefor, and a lever 14 with which to rock said blade and attached parts on their pivot, such pivot 85 consisting of a screw 15. There is a longitudinal slot 16 in the blade 6, and a longitudinal slot 17 in the stiffener 7. The screw 15 is received in the slots 16 and 17. All 90 these parts and members are old and well known both structurally and functionally.

Passing now to the new features it will be observed that there is a saddle 18 on the sole 1, upon which is mounted a frog 19. The saddle 18 is located between the 95 handles 4 and 5 and extends from cheek to cheek 3, and said saddle preferably has a central, longitudinal, raised portion which is exteriorly convex or arcuate in cross section. The bottom of the frog 19 is shaped 100 to fit and ride on the upper surface of the saddle 18, and thus is afforded a substantial support of sufficient size or area to render said frog stable and prevent any 105 sidewise or torsional movement on the part 100 of the frog. At the forward end of the frog is a downwardly and forwardly inclined projection 20 that bears at the bottom edge on the sole 1 behind or adjacent to the throat 9. Otherwise this frog is similar to 110

corresponding members in other planes, and the screws 13 and 15 are tapped into said frog in the usual manner.

By adjusting the frog 19 back and forth on the saddle 18 the cutting edge of the blade 6 is shifted in the throat 9 in the manner and to the extent desired. By this means and in this manner the throat clearance may be varied.

- 10 Slidely arranged in a bore through the longitudinal center of the saddle 18 is an adjusting rod or bar 21 which I term an adjuster. The forward end of the adjuster 21 is beveled to correspond with the inclination of the inner or rear side of the frog projection 20, and said projection is rigidly secured to such beveled end of said adjuster by means of a screw 22. Fastened securely to the rear protruding end of the adjuster 21, by means of a screw 23, is a link 24. An adjusting screw 25 is tapped into the back end of the saddle 18 at one side of the adjuster 21. The screw 25 has a head with an annular groove 26 therein to receive the end of the link 24 that is opposite to that which is attached to the adjuster, such end being bifurcated, as shown at 27 in Fig. 4, to enter said groove. Obviously if the screw 25 be turned inwardly the adjuster 21 with the frog 19 will be carried forwardly, through the medium of the link 24 and the screw 23, and if said first-named screw be turned outwardly said adjuster with said frog will be carried rearwardly, through the same medium as before. The handle 5 is in the central, longitudinal plane of the implement, and the adjusting screw 25 is a sufficient distance from one side of said plane to permit a screw-driver to be applied to said screw without interference on the part of said handle. In other words, the handle 5 forms no obstruction to the use of a screw-driver in adjusting the screw 25 to advance or retract the adjuster 21.
- 45 Locking means for the adjuster 21 is required, and the same consists of a binder in the form of a screw 28 which is tapped into said adjuster from above. The head of the screw or binder 28 is in the slots 16 and 50 17 in the blade 6 and stiffener 7, and from said head the shank of said screw extends downwardly and rearwardly through the frog 19, and a longitudinal slot 29 in the top of the saddle 18, into the adjuster 21. The 55 latter is broken away in Fig. 1 to show the binder 28 in full, also the screw 22. The slot 29 is covered by the frog 19. The head of the binder 28 is accessible for a screw-driver through the slot 11 in the clamp 10.
- 60 It follows, therefore, that the binder can be readily tightened and loosened by means of a screw-driver applied through the slot 11 to the head of said binder.

When the binder 28 is tightened it forces 65 the frog 19 on to the saddle 18 and the ad-

juster 21 against the top of the bore in said saddle for said adjuster, clamping the fixed and immovable saddle between said frog and adjuster or the two latter to the former, so that the adjuster with the frog and attached parts is held securely in place. Upon loosening the binder 28 the adjuster 21 can be moved freely to whatever extent may be necessary, since ample space for the movement in a direct line of said binder is provided by the slot 29. The binder also prevents or assists in preventing the adjuster from rotating on its axis, due to the fact that no movement sidewise of said binder is permitted by the sides of the slot 29.

To adjust the blade 6 in the throat 9, it is first necessary to loosen the binder 28, and then the screw 25 is turned to advance or retract the frog 19 to the desired extent. After this the binder is retightened.

More or less change in matters of size, shape, construction, and arrangement of some or all of the parts of the plane may be made without departing from the spirit of my invention or exceeding the scope of what is claimed.

What I claim as my invention, and desire to secure by Letters Patent, is—

1. In a plane, a frame provided with a saddle, an adjuster slidely arranged in said saddle, means to advance and retract said adjuster, a frog mounted on said saddle and rigidly attached to said adjuster, said frog being adapted to have attached thereto the customary slotted blade and blade members, and a binder for said adjuster, said binder being accessible through the slots in said blade and blade members.

2. In a plane, a frame provided with a saddle, an adjuster slidely arranged in said saddle, means to advance and retract said adjuster, said means being accessible from the rear, a frog mounted on said saddle and rigidly attached to said adjuster, said frog being adapted to have attached thereto the customary slotted blade and blade members, and a binder for said adjuster, said binder being accessible through the slots in said blade and blade members.

3. In a plane, a frame provided with a saddle, an adjuster slidely arranged in said saddle, means to advance and retract said adjuster, said means consisting in part of a screw which is accessible from the rear, a frog mounted on said saddle and rigidly attached to said adjuster, said frog being adapted to have attached thereto the customary slotted blade and blade members, and a binder for said adjuster, said binder being accessible through the slots in said blade and blade members.

4. In a plane, a frame provided with a saddle having an elevated longitudinal portion, an adjuster slidely arranged in said saddle, means to advance and retract said

adjuster, a frog mounted on said saddle and rigidly attached to said adjuster, the bottom of said frog conforming to the top surface of the saddle, and means to lock and release 5 said frog to and from said saddle.

5. In a plane, a frame provided with a saddle, an adjuster slidably arranged in said saddle, an adjusting screw tapped into the rear end of said saddle, a link connecting the rear end of said adjuster with 10 said screw, the arrangement being such that the adjuster can be advanced and retracted by turning said screw, a frog mounted on said saddle and rigidly attached to the front 15 end of said adjuster, and means to lock and release said adjuster.

6. In a plane, a frame provided with a saddle bored longitudinally and having a longitudinal slot in the top thereof, an adjuster in the bore in said saddle, means to 20 advance and retract said adjuster, a frog mounted on said saddle and rigidly attached to said adjuster, and a binder having a head outside of the blade-receiving face of the 25 frog, and extending through said frog and said slot into engagement with said adjuster, for locking and releasing purposes.

7. In a plane, a frame provided with a saddle bored longitudinally and having a longitudinal slot in the top thereof, an adjuster in the bore in said saddle, an adjusting 30 screw tapped into the rear end of said saddle, a link connecting the rear end of said adjuster with said screw, the arrangement 35 being such that the adjuster can be advanced and retracted by turning said screw, a frog mounted on said saddle and rigidly attached to the front end of said

adjuster, and a binder having a head outside of the blade-receiving face of the frog, 40 and extending through said frog and said slot into engagement with said adjuster, for locking and releasing purposes.

8. In a plane, a frame provided with a saddle, an adjuster slidably arranged in 45 said saddle, means to advance and retract said adjuster, said means consisting in part of a screw which is accessible from the rear, a frog mounted on said saddle and rigidly attached to said adjuster, said frog being 50 adapted to have attached thereto the customary slotted blade and blade members, and a binder adapted to clamp said frog and adjuster to said saddle, said screw being accessible through the slots in said blade 55 and blade members.

9. In a plane, a frame equipped with supporting means for a frog, a frog connected with said means, said frog being adapted to have attached thereto the customary slotted 60 blade and blade members, and locking means for said frog, said locking means being accessible through the slots in said blade and blade members.

10. In a plane, a frame provided with a saddle, a longitudinally movable member arranged in said saddle under the top portion thereof, a movable frog supported by said saddle, means to connect said frog with said longitudinally movable member, and 70 locking and releasing means for said frog and member.
